UNITED STATES PATENT OFFICE.

CECIL H. BALMAT, OF SAN FRANCISCO, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE.

LIQUID-FUEL BURNER.

Application filed March 22, 1926. Serial No. 96,523.

This invention relates to an oil burner for burning fuel oils, especially heavy fuel oils. In order to burn such oils satisfactorily it is necessary to effect a suitable atomization of the fuel, to provide the correct quantity of air, and to maintain the proper temperature during combustion. The burners which are used in industrial plants for burning heavy oils are usually either of a type in which steam, or sometimes air, under high pressure, is utilized to atomize the oil. Another type of burner is employed in which the oil is broken up by mechanical means, either by being forced to issue from a small orifice or from the periphery of a rapidly revolving cup. In domestic installations steam under high pressure is not available; neither is compressed air, and furthermore burners using these means for atomization are noisy in operation and require exact control, preferably by an expert. Burners using mechanical means for effecting the pulverization of the fuel are in general not very flexible under domestic conditions—that is to say, they are not readily adaptable for being changed from an adjustment for a small fire to an adjustment for producing a large fire. Furthermore, they require considerable cleaning. Those burners which utilize pressure alone for the atomization of the oil require high pressure pumps, and in small sizes, such as would be suitable for domestic use, the orifices are necessarily so small as to become very easily stopped up.

The general object of this invention is to overcome these difficulties and to produce a burner of simple construction which can be readily used for developing a small fire or a large fire; also to provide a construction in which the fuel oil will be adequately heated to promote its atomization, but in which the fuel is sufficiently protected from the furnace heat to prevent its reduction to a tarry or carbonaceous residue. A further object of the invention is to provide a burner of this type in which the fuel ducts are relatively large and placed so that they can be readily cleaned. A further object is to provide an oil burner having a special construction at its tip which develops a relatively large atomizing area or zone and which will bring the air blast into intimate contact with the oil.

A further object of the invention is to im-

prove the general construction of burners of this type.

55

Further objects of the invention will appear hereinafter.

The invention consists in the novel parts and combination of parts to be described hereinafter, all of which contribute to produce an efficient liquid fuel burner.

60

A preferred embodiment of the invention is described in the following specification, while the broad scope of the invention is pointed out in the appended claims.

65

In the drawing:

Figure 1 is a bottom plan of a burner embodying my invention.

70

Figure 2 is a longitudinal vertical section through the burner in its upright position.

Figure 3 is a longitudinal section through the inner nozzle which carries the liquid burner.

75

Figure 4 is a section taken about on the line 4—4 of Fig. 3, and further illustrating details of the invention.

Figure 5 is a section further illustrating details of the invention.

Figure 6 is a side elevation of the tip of the fuel nozzle with its outer shell removed, and particularly illustrating details of its inner shell.

80

In practicing my invention I provide an outer nozzle 1 for carrying an air blast which may be admitted through an opening 2 at the back end of the nozzle where a flange 3 is provided for attachment to the blast pipe. This outer nozzle has a mouth 4 at its forward or inner end at which the air blast is emitted and at this point the outer nozzle may be provided with a tapered tip 5.

85

Within the outer nozzle I provide an inner nozzle 6 for conducting the liquid fuel to the vicinity of the mouth 4. At its rear end this inner nozzle has an enlarged collar 7 which may fit into a bore 8 at the rear end of the outer nozzle, at which point it may be secured by a set screw 9. Near its inner end the outer nozzle is provided with a transverse bar 10, the middle point of which is formed into a hub 11 with a central opening 12 which receives a reduced neck 13 formed near the inner end of the nozzle. Beyond this hub 11, the inner nozzle is formed with a tip 14 which is of reduced size and preferably substantially wedge shape, as illustrated in Figs.

90

95

100

105

2 and 3. The inner nozzle 6 is of course of tubular form so that its interior forms a duct 15 for the liquid fuel which is admitted at a threaded connection 16 at the back end of the nozzle.

At the forward end of the inner nozzle and preferably within the mouth 4, I provide a fuel cap or fuel tip 17. This cap is constructed in the form of an annular shell with a double wall so that a narrow annular space 18 is formed around the longitudinal axis of the tip. This annular space is preferably so narrow that it will be capillary in its action. It is supplied with fuel through one of the annular walls, and this fuel finds egress at the annular line forming the extreme tip of the fuel nozzle.

The cap or fuel tip 17 preferably consists of an inner shell 19 which seats over the wedge-shape tip 14 of the inner nozzle and may be attached to the same by a cross pin 20 (see Figs. 3, 4 and 6). The tip 14 is provided with a duct 21 communicating with the duct 15 and terminating in a duct 22 of reduced diameter, which extends well up into the extremity of the tip 14, at which point it communicates with a transverse duct 23 in the end of the tip that emerges at the side edges of the tip (see Fig. 4). The inner shell 19 has two diametrically opposite openings 24 which communicate with the ends of this transverse duct 23. The tip or cap 17 also includes an outer shell 25 which is removably attached over the inner shell concentrically so as to produce the annular oil space 18. For this purpose, I prefer to provide the outer surface of the inner shell 19 with interrupted screw-threads 26 which co-operate with corresponding interrupted screw-threads formed on the inner face of the outer shell 25.

I prefer to construct these parts so that the inner diameter of the inner shell is considerably greater than the thickness of the tip 14 so that an air passage 27 is formed through the bore of the tip 17. By reason of this construction, when the air blast passes through the mouth 4, a considerable quantity of air passes through the interior of the fuel tip 17 and this produces a very efficient atomization of the fuel and gives a relatively large zone of atomization.

The quantity of liquid fuel admitted may be controlled by valves, not illustrated, which are in the fuel pipe connection, which is attached at the coupling 16.

In using this burner in a furnace, it should be set in the wall of the furnace as indicated by the dotted lines 28 in Fig. 2. Of course the furnace wall becomes heated from the flame within the furnace and the interior of the burner maintains a fairly high temperature, sufficient, at least, to enable the heavy fuel to flow freely through the inner nozzle. However, by reason of the fact that the air

blast surrounds the inner nozzle, it becomes impossible for the inner nozzle to become overheated under ordinary working conditions though the fuel will be adequately heated for atomization but without the production of tarry or carbonaceous residue in the fuel nozzle.

If desired, the outer nozzle may be provided with a gas duct 29 extending longitudinally in one of its walls, the mouth 30 of which is located near the tip of the burner. This enables a gas pilot light to be employed to light the burner when the fuel and air blast are turned on. It will be evident that the ducts for the fuel through the inner nozzle are relatively large so that they do not tend to clog up, and it will also be evident that by removing the outer shell 25 of the fuel tip, the annular space 18 can be readily cleaned and also the transverse duct 23.

Although this duct 23 delivers the fuel to the rear of the threads 26, it will be evident that by reason of the fact that this thread is interrupted, the gap 31 through the thread which is located opposite to the ends of the duct 23 enables the oil to move forwardly in the capillary space 18.

It is understood that the embodiment of the invention described herein is only one of the many embodiments this invention may take, and I do not wish to be limited in the practice of the invention, nor in the claims, to the particular embodiment set forth.

What I claim is:

1. In an oil burner, the combination of an outer nozzle for conducting an air blast and having a mouth at its forward end through which the air blast is delivered, an inner nozzle carried within the outer nozzle and having a fuel duct for the oil, said inner nozzle having a wedge shaped tip with a transverse fuel duct, for taking the fuel from the first named fuel duct, a delivery cap consisting of an inner annular shell encircling and attached to the said tip in said mouth, and an outer annular shell secured over the inner shell and co-operating with the same to form a substantially capillary space communicating with the transverse duct.

2. In an oil burner, the combination of an outer nozzle for conducting an air blast having a mouth at its forward end through which the air blast is delivered, an inner nozzle carried within the outer nozzle having a fuel duct for the oil and having a wedge-shaped tip with a transverse fuel duct emerging on the side edges of the said tip and communicating with the first named fuel duct, and a delivery cap consisting of an annular inner shell secured to the side edges of the tip of the inner nozzle in the said mouth and having a port therethrough communicating with the said transverse duct, said delivery cap including an outer annular shell secured over the inner shell and co-

- operating therewith to form a substantially capillary space receiving the fuel through said port.
3. In an oil burner, the combination of an inner nozzle for the oil having a wedge shaped tip with a fuel duct extending into the same, an annular shell encircling the tip and attached to the side edges of the tip so that there is an air passage on each side between the flat sides of the tip and the wall of the shell, said tip having a transverse duct emerging at the side edges of the tip communicating with the first named duct and having a port passing through the wall of said shell, and an outer annular shell detachably secured to the first named annular shell and co-operating therewith to form an annular substantially capillary space receiving the oil through the port.
- 20 4. In an oil burner, the combination of an outer nozzle for conducting an air blast, having a mouth at its outer end through which the air blast is delivered, an inner nozzle carried within the outer nozzle having a wedge shaped tip with a fuel duct for the oil passing into the said tip, an annular shell secured to the side edges of said tip so that there is an air passage on each side of the tip between the tip and the wall of the said shell, said tip having a transverse duct 30 emerging on the side edges of the tip for leading the oil through the wall of the said shell, and an outer shell detachably secured to the inner shell and co-operating therewith to form an annular substantially capillary 35 space for the oil.
5. In an oil burner, the combination of an inner fuel nozzle with a wedge shaped tip having a longitudinally disposed fuel duct therein, an inner tubular shell encircling the 40 wedge shaped tip seating against the side edges of the wedge shaped tip and secured to the tip, said burner having a transverse fuel duct in said tip communicating with the first named fuel duct, emerging at said side 45 edges and passing through the wall of the said tubular inner shell, and an outer shell of tubular form received over said inner shell with means for removably securing the same to the inner shell, said inner shell cooperating with 50 the wedge shaped tip to form an air passage through the inner shell on each side of the wedge shaped tip, said tubular shells co-operating to form an annular capillary space 55 for the fuel.

Signed at San Francisco, California, this 1st day of March, 1926.

CECIL H. BALMAT.
